(57) **CLAIM**

The ornamental design for a breastmilk warmer, as shown and described.

DESCRIPTION

FIG. 1 is a front, right perspective view of a breastmilk warmer of the present invention;

FIG. 2 is a front elevation view of the invention illustrated in FIG. 1;

FIG. 3 is a right side view of the invention illustrated in FIG. 1;

FIG. 4 is a rear elevation view of the invention illustrated in FIG. 1;

FIG. 5 is a left side view of the invention illustrated in FIG. 1;

FIG. 6 is a top view of the invention illustrated in FIG. 1;

FIG. 7 is a bottom view of the invention illustrated in FIG. 1;

FIG. 8 is a front, right perspective view of a lid of the breastmilk warmer illustrated in FIG. 1;

FIG. 9 is a bottom plan view of the lid of the breastmilk warmer illustrated in FIG. 1;

FIG. 10 is a cross-sectional view taken along lines 10-10 of FIG. 9;

FIG. 11 is a right side view of the lid of the breastmilk warmer illustrated in FIG. 1;

FIG. 12 is a left side view of the lid of the breastmilk warmer illustrated in FIG. 1;

FIG. 13 is a front elevation view of the lid of the breastmilk warmer illustrated in FIG. 1;

FIG. 14 is a rear elevation view of the lid of the breastmilk warmer illustrated in FIG. 1; and,

FIG. 15 is a top plan view of the lid of the breastmilk warmer illustrated in FIG. 1.

The broken lines in the drawings illustrate portions of the breastmilk warmer and form no part of the claimed design.

1 Claim, 12 Drawing Sheets
